UNITED STATES PATENT OFFICE.

DAVID W. BUSH, JR., OF BARTLEY, NEBRASKA.

COMBINED SETTING AND BROODING COOP.

1,387,682.

Specification of Letters Patent. Patented Aug. 16, 1921.

Application filed November 11, 1920. Serial No. 423,256.

To all whom it may concern:

Be it known that I, DAVID W. BUSH, Jr., a citizen of the United States, residing at Bartley, in the county of Redwillow and 5 State of Nebraska, have invented certain new and useful Improvements in Combined Setting and Brooding Coops, of which the following is a specification, reference being had to the accompanying drawings.

10 This invention relates to combined setting and brooding coops.

An important object of the invention is to provide a device of this character which is extremely simple in construction, and yet 15 contains numerous advantages calculated to reduce to a minimum the labor involved in handling setting and brooding hens and their broods; and furthermore consists in the construction and arrangement of the 20 coop in such a manner as to render the same extremely economical.

A further object of the invention is to provide a coop having an attached run, the run and the coop being connected by rigid 25 skids or sills, the coop being separated from the run by a removable sliding door.

A further object of the invention is to provide a coop having therein a removable 30 partition dividing the coop into two sections, one of which is adapted for the reception of the nest, the coop being further provided with a hinged door in the roof thereof permitting access at all times to the hen and her brood.

35 Other objects and advantages of the invention will become apparent throughout the course of the following description:

In the accompanying drawings, wherein for the purpose of illustration are shown preferred embodiments of my invention, and 40 wherein like reference characters designate like parts throughout:

Figure 1 is a sectional plan of a unit setting and brooding pen constructed in accordance with my invention;

Fig. 2 is a similar view of a multiple unit coop and pen;

Fig. 3 is a longitudinal sectional view taken through a unit coop, and

50 Fig. 4 is a transverse section taken through a multiple unit coop.

Referring now more particularly to the drawings, the numeral 10 indicates sills or skids, of which in the unit construction of 55 my device two are employed, one at each side of the coop and run. At one end the

sills 10 are covered by flooring boards, as at 11, to form a base for the coop. At each corner of this base vertical uprights 12 are disposed about which are secured the sides 60 14 of the coop. The side facing toward the uncovered ends of the skids 10 has only the upper section thereof covered, terminating above the floor as indicated at 14^a leaving 65 an opening at the bottom portion thereof 14 forming a passage to and from the coop.

Secured to the sills 10, exteriorly of this wall, are vertical uprights 15, and intermediate these uprights and the adjacent uprights 12 of the coop proper is slidably 70 mounted a door 16, forming a removable closure for the opening left in the side walls. A removable board 17 is provided of sufficient length to extend diagonally across the coop and abut the side faces of the uprights 75 12 thereof at their juncture with the wall. This board 17 serves through the nesting period to divide the coop into two portions one of which may be employed as a nest. Subsequently to the hatching of the eggs 80 the board may be readily removed, as will hereinafter appear, and the nests likewise removed to afford plenty of room for the hen and her brood.

A roof is provided embodying rafters 18 85 which are adapted to abut and rest upon the upper ends of the vertical members 12 and which are held in the proper position by spaced horizontally extending lath 18^a, the spaces between the lath permitting ventilation 90 through the coop. These rafters 18 are covered preferably by shiplap in such a manner as to form the roof with projecting eaves, one of which overhangs the exposed ends of the skids 10. This edge is provided with a longitudinally extending strip 19 combining with the roof to form a gutter to prevent precipitation of the water from the roof into the pen of the coop. The opposite side of the roof embodies a hinged 100 section 20 forming a door by means of which access may be had to the roof and through which the door 17 or nest boards may be removed.

At the upper ends of the sills 10 are disposed vertical uprights 21 which combine with the post 15 to provide the corners of the pen. The pen is formed by securing to the sides of the vertical uprights 15 and 21, spaced lath or strips 22 and likewise closing the end in this manner. The upper portion of the run is closed by a cover 23

which is likewise preferably formed of spaced strips secured in any suitable manner.

It will be obvious to those familiar with the art that the construction hereinbefore set forth lends itself very readily to the multiple unit construction. If such a construction is desired, as for example a double unit, an extra skid 10 is provided which forms 5 the demarkation or the central line, dividing the coops and runs. The floor of the coop is laid across the skids in the usual manner and is divided centrally by placing thereon at opposite sides bars or vertical uprights 24 10 spaced apart a distance sufficient to permit the insertion therebetween of a partition 25. The pen is divided centrally by posts 27 and 28 having the dividing wall 29 secured thereto and formed of spaced strips, as hereinbefore disclosed.

It will be obvious that the construction as hereinbefore set forth is capable of some change without in any manner departing from the spirit of my invention: and I, 25 therefore, do not limit myself to such specific structure, except as so limited by the subjoined claims.

What I claim is:

1. In a setting and brooding coop, a rectangular floor, vertical uprights secured to said floor at the corners thereof, side walls secured to said uprights, a removable diagonally disposed partition within the coop and abutting the side faces of diagonally opposed vertical uprights at their junction with the side walls, and a roof for said coop comprising pairs of rafters adapted to abut and rest upon the vertical ends of said uprights, spaced transverse members having 30 their ends secured to the rafters of each pair and a weather-proof covering for said rafters, said covering being provided with a hinged portion forming a door through which said partition may be removed.

2. In a setting and brooding coop, a pair of spaced parallel sills, a rectangular floor secured to said sills at one end thereof, the sills projecting beyond the edge of the floor at one side thereof, vertical uprights secured 35 to said floor at the corners thereof, side walls secured to said uprights, the side wall next adjacent the exposed ends of said sills being discontinued at a point spaced from the floor to provide an opening, vertical uprights secured to said sills adjacent the last-named side wall, a slide disposed intermediate said last-named uprights and the end of the coop formed by said last-named side wall and closing the opening formed therein, vertical 40 uprights secured to the ends of said sills remote from said floor, spaced strips con-

necting said last-named uprights, spaced strips connecting said last-named uprights and the uprights adjacent the last-named wall, said first and last named strips combining with said uprights and the coop to form a pen, a cover for said pen and a roof for said coop. 65

3. In a setting and brooding coop, a pair of spaced parallel sills, a rectangular floor secured to said sills at one end thereof, said sills projecting beyond the edge of the floor at one side thereof, vertical uprights secured to said floor at the corners thereof, side walls secured to said uprights, the side wall next adjacent the exposed ends of said sills being discontinued at a point spaced from the floor to provide an opening, vertical uprights secured to said sills adjacent the last-named side wall, a slide disposed intermediate said last-named uprights and the end of the coop formed by said last-named side wall and closing the opening formed therein, vertical uprights secured to the ends of said sills remote from said floor, spaced strips connecting said last-named uprights, spaced strips connecting said last-named uprights and the uprights adjacent the last-named wall, said first and last named strips combining with said uprights and the coop to form a pen, a cover for said pen and a roof for said coop. 70

4. In a setting and brooding coop, a rectangular floor, vertical uprights secured to said floor at the corners thereof, side walls secured to said uprights, spaced pairs of uprights secured to said floor at opposed sides thereof and abutting opposed walls approximately centrally thereof, a partition extending transversely of said floor and having its ends disposed intermediate the spaced pairs of uprights and a removable diagonally disposed partition within the coop at each side of said partition and abutting side faces of corresponding vertical uprights of said last-named pair and of the vertical uprights secured to the corners of said floor diagonally opposed thereto. 105

In testimony whereof I hereunto affix my signature.

DAVID W. BUSH, JR.
